UNITED STATES PATENT OFFICE.

JAMES M. TRIER, OF NEW YORK, N. Y.

OFFSET-WEB CLEANER FOR PRINTING-PRESSES.

1,287,524.

Specification of Letters Patent. Patented Dec. 10, 1918.

Application filed February 7, 1917. Serial No. 147,054.

To all whom it may concern:

Be it known that I, JAMES M. TRIER, a citizen of the United States, and a resident of the city of New York, borough of the Bronx, 5 in the county of Bronx and State of New York, have invented a new and Improved Offset-Web Cleaner for Printing-Presses, of which the following is a full, clear and exact description.

10 Among the principal objects which the present invention has in view are: to extend the useful life of an offset web; to prevent the accumulation of smutting or blurring substances on said web; to smooth said web 15 before introducing the same to the packing roller; to provide apparatus for the accomplishment of the above-stated purposes which are interchangeable and quickly adjustable; and to concentrate the accumulated debris collected from said web.

Drawings.

Figure 1 is a longitudinal vertical section showing diagrammatically, the arrangement 25 of printing, packing and web-winding cylinders and guide rollers connected therewith as embodied in presses of conventional make, together with a cleaner for said web constructed and arranged in accordance with 30 the present invention;

Fig. 2 is a plan view of said cleaner;

Fig. 3 is a cross section of the cleaner on an enlarged scale, the section being taken as on the line 3—3 in Fig. 2;

35 Fig. 4 is a longitudinal section on an enlarged scale, showing a fragment of said cleaner and pivot therefor, the section being taken as on the line 4—4 in Fig. 2;

Fig. 5 is a detail view on an enlarged 40 scale, and in longitudinal section, the section being taken as on the line 5—5 in Fig. 2;

Fig. 6 is a cross section of the same, the section being taken as on the line 6—6 in Fig. 2.

Description.

The usual practice in most of the improved presses is to print both sides of the web in a single passage through the press.

50 To accomplish this the web 11 indicated in the present drawings and shown best in Fig. 1 thereof, is primarily printed on one side by a plate roller before introducing it to the plate roller shown in Fig. 1. The printed side of the web 11 prior to reaching the roller

12 is, of course, the side turned away from the said roller.

To prevent the transfer of the wet ink of the previously printing operation to the packing roller 13, an offset web 14 is used. 60 This web covers the surface of the packing roller 13 with which the web 12 is in contact. The web 14 therefore backs or lies in close contact with the web 11, and by moving synchronously therewith, all danger of 65 smudging the wet ink on that side of the web 11 is avoided. It is obvious that while in contact with the wet sheet or web 11, a portion of the wet ink is transferred to the offset web 14. 70

The offset web 14 is wound on the drum 15, which is supported on the synchronized driving rollers 16 to be rotated thereby at a peripheral speed equal to the travel of the web 11. In this manner is avoided any tendency 75 to pull the offset web 14 in advance of the web 11.

It is obvious that the ink deposit on the offset web 14 is held between the convolutions thereof when the same is rolled on the 80 drum 15. When in accordance with the usual custom the drums 15 and 17 are reversed and the web 14 is fed in the reverse direction from that indicated in Fig. 1 of the drawings, the inky deposit on the said 85 web is transferred to the web 11 when passing between the rollers 12 and 13. To overcome this objection is the principal object of the present invention, and to this end is employed the cleaner shown best in Fig. 2 of 90 the drawings.

The said cleaner has a stationary hanger frame 18. The frame 18 is provided at the opposite ends thereof with hanging straps 19, each of which is furnished with a vertical slot 20, through which bolts for suspending the frame 18 are passed to be secured in the frame of the printing press to which the cleaner is attached. The length of the slots 20 is sufficient to permit vertical 100 adjustment of the ends of the frame 18 to lift the rubbing bars above the plane coincident with the lower edges of the guide rolls 21 of the printing press as shown in Fig. 1 of the drawings. 105

The frame 18 has at the longitudinal center thereof, alined oppositely-disposed saddles 22. The saddles 22 are semi-circular, the center of the curve being coincident with the tops of the rubbing blades 23 whereon 110

rests the under surface of the offset web 14. In other words, the centers or curved surfaces of the saddles 22 are in service, in the plane with the offset web 14. In this manner, provision is made to avoid shifting the said offset web 14 when the blades 23 are rocked.

Each of the blades 23 is bent at its center to form a sharp angle. The side extensions 10 of said blades from said angles operate to smooth or spread each side of the web 14 as the same is drawn over the said blades.

The blades 23 are mounted on an elongated rectangular frame having side bars 15 24 and a series of cross bars 25. Centrally disposed and attached to the side bars 24 are curved pivot rockers 26. The curvature of the rockers 26 as shown best in Fig. 4 of the drawings, corresponds with the 20 curved seats of the saddles 22. For this reason when the frame carrying the blades 23 is locked on its center, the movement is coincident with the plane of the web 14 resting on said blades. The pins 27 are inserted 25 through the sides of the frame 18 and in service extend above the rockers 26 to prevent lifting said rockers from the saddles 22.

The rocking frame above described is provided with rubbing blades 28 and 29, said 30 blades being bent to a more obtuse angle than the blades 23. The inclination of the lateral sections of said blades is in a similar 35 direction to that of the lateral sections of the blades 23. The rocking frame is normally held level by springs 30. The springs 30 are guided by the pins 31, which, as shown best in Fig. 3 of the drawings, are made fast to the end cross bars of the stationary frame 18.

40 By placing the frame 18 so that the web 14 is elevated slightly above the lower level of the guide rolls 21, a gentle tension is exerted on the web 14 by the blades 23, 28 and 29. The pressure of the web 14 on the said 45 blades provides a frictional contact of the web so that the same is brought within the influence of the angularly-disposed sections of the blades, which tends to lead the web in the direction of the inclination. Both 50 sections being inclined from the center of the web, the result is that the web is slightly drawn or spread from its center.

When a printing press employing an offset web such as indicated by the numeral 14, 55 is equipped with a cleaner constructed and arranged in accordance with the present invention, the caked or surface-adhering ink or

other deposit is removed from the surface of said web before the same is brought into contact with the web 11. The blades 23, 28 and 60 29 operate to break the deposit from the surface of the web 14 rather than to scrape the same. This is due to the adhesion of the deposit accumulated at the edge of each of said blades.

65 It is obvious that the web 14 is liable to become stretched or contracted in sections adjacent either of the lateral edges thereof. The slackness or tightness of the web resulting from this is accommodated by the rock 70 of the frame and the blades 23, 28 and 29 mounted thereon.

75 It is obvious that by moving a cleaner such as described, the service life of an offset web is augmented and smudging or defacing the web being printed is avoided.

Claims.

1. The combination of a printing press and an offset web therefor; a cleaner for said 80 web embodying rigid rubbing members disposed transverse said web in supporting relation thereto; means for keeping said web in contact with said rubbing members; and means for pivoting said members for rocking 85 in correspondence with the pressure on said web, said means embodying a pivot, the axis whereof is in a plane coincident with said web.

2. The combination of a printing press 90 and an offset web therefor; a cleaner for said web embodying rigid rubbing members disposed transverse said web in supporting relation thereto; means for keeping said web in contact with said rubbing members; and 95 means for pivoting said members for rocking in correspondence with the pressure on said web, said means embodying a pivot, the axis whereof approximates the plane of 100 said web.

3. The combination of a printing press and an offset web therefor; a cleaner for said 105 web embodying rigid rubbing members disposed transverse said web in supporting relation thereto; means for keeping said web in contact with said rubbing members; and means for pivoting said members for rocking in correspondence with the pressure on said web, said means embodying a pivot, the axis whereof is in a plane coincident with 110 and adjacent the upper edge of said members.

JAMES M. TRIER.
